UNITED STATES PATENT OFFICE

HENNEN J. BLANTON, OF BROOKLYN, NEW YORK, ASSIGNOR TO INTERNATIONAL COMBUSTION ENGINEERING CORPORATION, OF NEW YORK, N. Y., A CORPORATION OF DELAWARE

BOILER BAFFLE

Application filed December 24, 1928. Serial No. 328,138.

This invention relates to boiler baffles and particularly to transverse or cross baffles for grouped boiler tubes.

One of the primary objects of my invention 5 is the provision of a transverse baffle for grouped boiler tubes which is of simple construction, easy to install and easy to take down.

Another object of my invention is the provision of a transverse baffle for boiler tube banks of such character that only a small portion of the baffle need be taken down in making tube replacements.

Another object of my invention is the provision of a tiled transverse baffle for boiler tube banks.

How the foregoing, together with such other objects and advantages as may herein-after appear, or are incident to my invention, 20 are realized is illustrated in preferred form in the accompanying drawings, wherein—

Fig. 1 is a more or less diagrammatic sectional elevation of the main parts of a vertical tube boiler illustrating an application of my 25 improved baffle.

Fig. 2 is an enlarged plan section of a portion of the middle bank of tubes of the boiler, the section being taken on the line 2—2 of Fig. 1 and just above the cross or transverse 30 baffle.

Fig. 3 is a front view of Fig. 2, and

Fig. 4 is an end view of Fig. 3 looking toward the right.

The portion of the boiler illustrated in 35 Fig. 1 comprises a lower mud drum 5, a pair of upper steam and water drums 6 and 7, a front bank of tubes 8 connecting the mud drum 5 to the front upper drum 6, a second or middle bank of tubes 9 also connecting the 40 drums 5 and 6, and a rear bank of tubes 10 connecting the drum 5 with the upper drum 7.

A baffle 11 is located at the front of the middle bank 9 and extends upwardly from the lower drum 5 to a point short of the upper 45 drum 6, at which point is located the cross or transverse baffle 12 which will be described in detail hereinafter. Other baffling is provided for the boiler as indicated at 13, 14, 15 and 16. The gases from the combustion chamber pass upwardly over the tubes of 50

the front bank 8, across the tubes of the middle bank 9 above the baffle 12 into the space between the middle and rear banks and from thence pass downwardly over and amongst the portion of the middle bank located below 55 the baffle 12 and finally pass upwardly over and amongst the tubes of the rear bank.

Referring now more particularly to Figs. 2, 3 and 4, it will be seen that the grouped tubes of the bank 9 are arranged in a plurality of spaced rows 17, 18, 19, 20, and so on, and that the baffle 12 is constructed of a plurality of tile members and supports therefor, the particular arrangement of which is as follows: Taking, for example, the two adjacent rows of tubes 19 and 20, it will be noted that a plurality of split tiles each comprising two parts 21 and 22 are located in the space between the rows. Each tile part is provided with grooves or sockets 23 adapted to fit the tubes so that displacement or shifting of the tiles laterally is prevented. As these grooves are substantially semi-circular, the tile parts so fit the tubes that no space, other than that needed for ease of assembly 60 65 70 75 80 85 90 95 100

and for contraction and expansion purposes, is left between adjacent tubes of the rows. In order to support the tiles I have provided the members 24 in the spaces between rows which, in this instance, are in the form 80 of angle irons. The angle irons are supported from tubes of the rows as by means of the securing means or U-bolts 25 which are readily detachable. As shown in the drawings, each row of tubes is provided with 85 an angle iron support which is common to all of the tile parts in the space in which the support is located.

The tiles may be of any suitable length, and in the drawings in which each row of tubes comprises an odd number of tubes, I have shown some of tile parts as having two tube grooves and others, for example, parts 21a and 22a, as having three tube grooves.

The row of tiles 26 between the row of tubes 17 and the furnace wall 27 is supported by plates 28 laid upon the angle iron 24 of the row of tubes 17. The tiles of this row are placed as the wall 27 is installed.

From the foregoing it will be seen that I have provided a very simple tile baffle which can be easily installed and taken down. Among other advantages tube replacements may be made by only removing a few of the tiles which are located adjacent to the tube or tubes to be replaced and without disturbing the balance of the baffle. To remove the tiles one part thereof is slid up along the tubes to clear the other part, which other part may then be removed.

I claim:—

1. In combination, boiler tubes arranged in grouped spaced vertical rows, angle irons located in the spaces between said rows and extending crosswise of the tubes, U bolts engaging tubes of the rows and one of the flanges of the angle irons for clamping the angle irons in position, the other flanges of the angle irons constituting shelves in the spaces between the rows of tubes, and a plurality of split tiles resting on said shelves.
2. In combination, boiler tubes arranged in grouped spaced vertical rows, angle irons located in the spaces between said rows and extending crosswise of the tubes, U bolts engaging tubes of the rows and one of the flanges of the angle irons for clamping the angle irons in position, the other flanges of the angle irons constituting shelves in the spaces between the rows of tubes, and a plurality of split tiles resting on said shelves, said split tiles having sockets fitting the tubes.
35. In testimony whereof I have hereunto signed my name.

HENNEN J. BLANTON.
